UNITED STATES PATENT OFFICE.

CLARENCE VOGT, OF WENONAH, NEW JERSEY, ASSIGNOR TO VOGT BROS. & SQUIER COMPANY, OF PHILADELPHIA, PENNSYLVANIA, A CORPORATION OF DELAWARE.

LATCH.

Application filed March 30, 1923. Serial No. 628,704.

This invention relates to latches for doors and more particularly to latches for the doors of automobiles, carriages and similar vehicles, said latches being commonly known 5 in the trade as sheet metal or limousine latches, and among other objects had in view I aim to provide a latch of the foregoing character which is typified by a substantial structure, while being very compact in 10 design.

Other objects inhering to my invention are the provision of a sheet metal latch the several parts whereof, when in assembled relation, are securely connected by a single binding post or pin; the effective prevention of its component parts becoming detached or dislodged consequent upon the constant vibration to which latches of the foregoing specified character are subjected; and one 20 that is effective in its operation and particularly serviceable in use.

Still further I aim to, and do, provide a sheet metal lock that, while embodying the advantageous features above referred to, is 25 of simple and efficient construction and capable of manufacture at a comparatively low cost.

With the foregoing objects in view this invention consists essentially in certain novel 30 features of construction and the combinations and arrangements of parts incorporated in the latch hereinafter fully set forth, and more particularly defined by the subjoined claims.

In the further disclosure of this invention, reference will be had to the accompanying 35 sheet of drawings constituting a part of this specification and in which like characters of reference designate the same or corresponding parts in all the views.

Figure I, is an elevation of one practical embodiment of my invention, or novel sheet metal latch, with part of the base member broken away for a clearer view of the underlying structure.

Figure II is a reverse elevation of the preceding figure.

Figure III is a sectional view taken substantially on the line III—III in Figure I, and looking in the direction of the arrows.

Figure IV is a perspective view of the latch and associated stirrup or fork.

Figure V is a perspective view of the latch actuator or tumbler.

Figure VI is a perspective view of a modified form of the latch actuator.

Figure VII is an axial vertical section through the form of latch actuator hub shown in the preceding figure.

Figure VIII is a perspective view of a further modified form of the latch actuator; and

Figure IX is an axial section through the same.

Referring more in detail to the drawings and in accordance with the specific embodiment of my invention illustrated thereby the base member or latch plate 10 is made of sheet metal of appropriate character and thickness. This base member or latch plate 10 embodies a blank of rectangular configuration that is bent along three of its sides to provide flanges 11 at right angles thereto, and along the fourth side to provide a face plate 12, having countersunk holes 13 therein for the insertion of the necessary attaching screws in the well known manner. Thus it will be seen that the said base member or latch plate 10 when formed to provide the flanges 11 and face plate 12 constitutes what may be termed a unitary latch case. The face plate 12 is suitably slotted at 14 for the free passage of the latch 15, and it has additional spaced slots or openings 16 therein, for a purpose hereinafter set forth.

The latch member 15 is made from a substantially rectangular sheet metal blank stamped out or cut away from one of its sides into U-formation to provide a slot 17 and a pair of spaced limbs 18, the free ends whereof are transversely bent at right angles to constitute supports 19 having central projections 20 which it is to be remarked are rectangular in cross section and serve to guidingly maintain the latch member in proper alignment as hereafter explained. The latch bolt 21 is made of rectangular cross section bar material and it is slotted at 22 from its inner end to receive a slotted extension 23 medial of the aforesaid sheet metal blank 15, union of the two parts 15 and 21 being effected by means of depression 24 appropriately forced into said slotted extension 23 from the outer face of the latch bolt 21. Or, as will be quite obvious, the parts 15, 21 may be spot-welded or riveted together, but it being my aim to produce the entire latch by die stamping, it will be seen

that the forcing of the depression 24 will result in an opposed displacement of metal into the aforesaid slot 22, the same being readily comprehended by those conversant 5 with the art to which my invention appertains.

Referring again to the aforesaid rectangular projections 20 it is to be observed that they are a sliding fit in elongated and 10 parallel spaced slots 25 in the main body portion of the base member or latch plate 10, as best seen by Figure I, and they serve to maintain and guide the latch 15 with a direct travel and free from any undulatory 15 movement.

The latch actuator or tumbler 26 is conveniently, also, a unitary metal stamping provided with opposed actuating wings 27, 27, and stepped hub 28 having a rectangular bore 29 for the reception of the usual 20 operating spindle or lever—not shown. The usual spring is indicated at 30, and it is appropriately coiled around and anchored on a binding post or pin 31, with one free end 25 32 abutting one of the aforesaid supports 19, while the other free end 33 has bearing on the abutting flange 11 as will be readily seen from Figure I, more particularly.

The mechanism above described is conveniently maintained, and securely held, in assembled relation by means of a complementary plate 34 having ears or lugs 35 adapted to enter and snugly seat in the spaced slots 16, while said plate 34 is apertured at 36 to receive the shouldered part 37,—Fig. III—of the aforesaid binding post or pin 31. This complementary plate 34 is also cut out or slotted at 38 to provide an additional guiding means for the latch bolt 40 21, while it may have its spindle hole 39 inwardly flared or swaged at 40, to form a spacer bearing for the aforesaid latch actuator or tumbler 26 that prevents its displacement, as will be obvious on an examination 45 of Figure III more particularly.

In some cases, where it may be desirable that the latch actuator or tumbler 26 have rotatable bearing in both the base member 10 and the complementary plate 34, I may use the tumbler or actuator 26'—shown in Figures VI and VII, the same simply embracing a pair of the hereinbefore described actuators or tumblers 26 disposed in reversed relation and spot welded together; or, they 50 need not be so connected, but it will be noted that by reversing said tumblers 26 in opposed relation there will be provided a shouldered bearing 41 at each side or hub end. Furthermore, in other instances, where it is requisite that the latch actuator or tumbler wings 27 be relatively nearer one end of the hub portion 26 than the other, I use the device 26'' illustrated in Figures 55 VIII and IX, said device 26'' embracing a substantially rectangular spindle hub 42 on

the outer wall whereof, the actuator or tumbler 26—in this case a flat member—is suitably forced, shrunk or otherwise rigidly secured.

From the foregoing description and an examination of the drawings it will be clearly apparent that by my invention there is provided a sheet metal latch embodying but few parts, all of which can be easily produced by die stamping, while the assemblage of said parts can be effected with a minimum expenditure of time and labor. Still further it will be remarked that the respective moving parts or members are efficiently designed and correlated to eliminate friction, while ensuring relative movement without the remotest possibility of disruption. Finally I wish it understood that I do not limit myself to the precise form of sheet metal latch hereby exemplified and fully explained, but deem myself at liberty to make all such reasonable variations and modified arrangements as fairly lie within the scope of the appended claims.

Having thus described my invention, I claim:

1. In a latch of the type described, the combination of a sheet metal casing having integral flanges and a slotted face plate, a latch member movable through the slotted face plate and provided with a forked extension having angled terminal ends slidable in parallel slots in the aforesaid casing, a sheet metal actuator journaled in the casing and having opposed wings operatively engaging the angled terminal ends, and a closure plate having an inwardly swaged flare concentric with the actuator hub.

2. In a latch of the kind described, the combination of a sheet metal casing having integral flanges and a slotted face plate, a latch member in said casing having an attached sheet metal forked extension the terminal ends whereof are turned at right angles thereto, said terminal ends being slidably in parallel slots in the aforesaid casing body, a unitary sheet metal actuator journaled in the casing and embodying opposed wings operatively engaging the terminal ends, and a complementary closure plate having an inwardly swaged flare in register with the actuator hub.

3. In a latch of the kind described, the combination of a sheet metal casing having integral flanges and a slotted face plate, a latch member in said casing having an attached sheet metal forked extension the terminal ends whereof are turned at right angles thereto, said terminal ends being slidably in parallel slots in the body of said casing, a unitary sheet metal actuator engaging the terminal ends, said actuator having a stepped spindle bore, and a complementary closure plate having an inwardly swaged flare in register with the actuator hub.

4. In a latch of the kind described, the combination of a sheet metal casing having integral flanges and a slotted face plate, a closure plate, a latch member movable in said casing and having an attached sheet metal forked extension the terminal ends whereof are turned at right angles thereto, said terminal ends being provided with pintles slidable in parallel slots in the casing, 25 and a sheet metal actuator comprising wing members affording an outwardly stepped bearing portion, said bearing portion being adapted for journalling in the sheet metal casing body and complementary closure plate, and said complementary plate having lugs fitted in 30 corresponding slots in the face plate and being locked to a shouldered binding post in said casing.
- 10 5. In a latch of the kind described, the combination of a sheet metal casing having integral flanges and a slotted face plate, a complementary closure plate, a latch member movable in said casing and having a connected sheet metal forked extension the terminal ends whereof are turned at right angles thereto, said terminal ends being provided with rectangular section pintles slid- 35 able in parallel slots in the casing, a sheet 40

metal actuator comprising wing members affording an outwardly stepped bearing portion, said bearing portion being adapted for journalling in the sheet metal casing body and complementary closure plate, and said complementary plate having lugs fitted in 30 corresponding slots in the face plate and being locked to a shouldered binding post in 25 said casing.

6. In a latch mechanism of the kind described, the combination of a sheet metal 35 casing having an integral surrounding flange and slotted face plate, a complementary closure plate having lugs for insertion in corresponding slots in the face plate, opposed apertures in said casing and closure plate, 40 one of which is inwardly flared, and means for securely locking said closure plate to the casing in spaced relation.

In testimony whereof, I have hereunto signed my name at Philadelphia, Pennsylvania, this 27th day of March, 1923. 45

CLARENCE VOGT.
